OTHER PUBLICATIONS

Pending unpublished U.S. Appl. No. 29/252,435, entitled "Cutting Blade Sleeve." Filed by Nathan J. Abbas, et al. on Jan. 23, 2006. Drawing Figs. 1-3 are attached hereto.

Photograph showing a plastic blade package produced by Crescent Mfg. Co., incorporating a plurality of blade compartments extending from a non-compartmented, non-sealed portion. The blade compartments are non-separable.

(Continued)

Primary Examiner—Mitchell I. Siegel*Assistant Examiner*—Mark A Goodwin(74) *Attorney, Agent, or Firm*—James R. Eley; Michael A. Forhan; Eley Law Firm Co.(57) **CLAIM**

The ornamental design for a blade package, as shown and described.

DESCRIPTION

FIG. 1 is a top perspective view of the blade package showing my new design;

FIG. 2 is a top plan view thereof;

FIG. 3 is a bottom plan view thereof;

FIG. 4 is a right side elevation thereof;

FIG. 5 is a left side elevation thereof;

FIG. 6 is a first end elevation thereof; and,

FIG. 7 is a second end elevation thereof.

The long dash short dash broken line showing of a blade and the short dash broken line showing of a series of packages and a blade is included for the purpose of illustrating environmental structure and forms no part of the claimed design.
